Assistant Examiner — James T Tyree

(57) **CLAIM**

The ornamental design for a toy locking element as shown and described.

DESCRIPTION

- 1.1: Perspective
1.2: Perspective
1.3: Right
1.4: Left
1.5: Front
1.6: Back
1.7: Top
1.8: Bottom

1.1 is a top and right perspective view of a toy locking element showing our new design; 1.2 is a top and left perspective view thereof; 1.3 is a right view thereof; 1.4 is a left view thereof; 1.5 is a front view thereof; 1.6 is a back view thereof; 1.7 is a top view thereof; 1.8 is a bottom view thereof; the line shading in reproductions 1.1-1.8 is a drawing convention to represent contours, it does not illustrate any surface ornamentation and/or decoration.

1 Claim, 8 Drawing Sheets
